UNITED STATES PATENT OFFICE.

JASPER N. RALSTON, OF FITZGERALD, GEORGIA.

STEAM-BOILER ASH-PAN.

1,348,737.

Specification of Letters Patent.

Patented Aug. 3, 1920.

Application filed February 19, 1918. Serial No. 218,122.

To all whom it may concern:

Be it known that I, JASPER N. RALSTON, a citizen of the United States, residing at Fitzgerald, in the county of Ben Hill and 5 State of Georgia, have invented certain new and useful Improvements in Steam-Boiler Ash-Pans; and I do hereby declare the following to be a full, clear, and exact description of the invention, such as will enable 10 others skilled in the art to which it appertains to make and use the same.

The invention relates to a steam boiler ash pan.

The object of the present invention is to 15 provide a simple, practical and efficient steam boiler ash pan designed particularly for use on railroad locomotives and to eliminate the expense, delays and loss resulting from the use of locomotive ash pans of the ordinary 20 construction.

The ash pans ordinarily in use on locomotives do not hold their original shape when 25 hot coal, ashes and clinkers accumulate within them. The hot substance warps the metal and opens the joints, allowing live coals to drop through and set fire to bridges, roadbeds, grass and the like, causing often considerable loss which results in expensive law suits and damages.

30 It is also an object of the present invention to provide an ash pan equipped with means for maintaining it in a relatively cool condition and for delivering water upon hot coals, clinkers and ashes, and of enabling 35 the same to be discharged in a safe condition.

Furthermore, the invention has for its 40 object to reduce the expense of the ash pan in the original construction, lessen the cost of the upkeep and provide a pan which will be practically indestructible from warping and which will last for a comparatively long time.

With these and other objects in view, the 45 invention consists in the construction and novel combination of parts hereinafter fully described, illustrated in the accompanying drawing and pointed out in the claims hereto appended; it being understood that various changes in the form, proportion, size and 50 minor details of construction within the scope of the claims, may be resorted to without departing from the spirit or sacrificing any of the advantages of the invention.

In the drawing:

55 Figure 1 is a longitudinal sectional view

of a locomotive ash pan constructed in accordance with this invention.

Fig. 2 is a transverse sectional view taken on the line 2-2 of Fig. 1.

Like numerals of reference designate corresponding parts in the several figures of the drawing.

In the accompanying drawing, in which is illustrated the preferred embodiment of the invention, the locomotive ash pan is 60 equipped with side and end walls composed of inner and outer sheets 1 and 2 spaced apart to form an intervening water space 3 which communicates with water spaces 4 and 5 of bottom sections 6 and 7. The bottom 65 sections 6 and 7 are composed of inner and outer sheets spaced apart to form the intervening water spaces 4 and 5 and they are oppositely inclined as shown and are located between outlets 8 which are controlled by 70 slides 9 mounted upon and guided by angle bars 10.

The inner sheet of the side and end walls terminates short of the upper edge of the outer sheet and the upper edge of the said 75 inner sheet is spaced from the outer sheet to form an outlet 11 to permit the water, after filling the water spaces 3, 4 and 5, to overflow the inner sheets and flow down the face of the walls of the ash pan for cooling 80 the same and also for cooling the hot cinders, ashes and coals, whereby the same will be effectively extinguished before they are discharged at the outlets 8 by the operation of the slides 9.

90 The open spaces at the top of the side and end walls of the ash pan are covered by aprons or shields 12 composed of an upper attaching flange 13, an inwardly projecting horizontal connecting portion or web 14 and 95 an inclined downwardly extending flange 15. The horizontal web or flange 14 and the inclined flange 15 are arranged in spaced relation with the upper edge of the inner sheet 1 so as not to interfere with the overflow 100 of the water from the side and end water spaces 3. The aprons or shields are adapted to prevent ashes and other accumulation from closing the overflow outlet and interfering with the action of the water.

105 The ash pan is equipped with a hopper 16 mounted on the ash pan exteriorly of one end and consisting of an inclined bottom or side wall 17 and a horizontal top wall 18 which is provided with a filling opening 110

19. The end wall is provided in its outer sheet with an opening 20 constituting an outlet for the water to permit the same to flow from the hopper into the water space 5 3. The hopper may be connected with any suitable means for supplying the necessary amount of water. The overflow from the injector may be employed and will overflow the ash pan each time the injector is 10 operated. Also the water from the exhaust pipe of the air pump and waste water from other appliances operated by steam may be used and a connection can be made directly with the water tank if necessary and can 15 be controlled by suitable means for enabling the water space to be kept full and overflowing at all times. The water will keep the inside ash pan sheets cool and thereby prevent the pan from warping and 20 will maintain it in proper alignment. The water is fed into the hopper on the outside sheet of the pan and when the water space between the inner and outer sheets is full, the water overflows around the pan from 25 under the wings of the apron or shield and runs down the inside sheet, extinguishing all live fire which may collect against the inside sheet. The water also runs down around the slide openings or outlets, thereby 30 keeping the live fire out and preventing the slides or angle irons from warping. By this construction and operation there is no liability of fire leaving the ash pan and damaging the road bed or other property. The 35 arrangement with ordinary care will be practically indestructible from warping and will last for a long time in proper working order. The sides of the ash pan are provided with inclined extensions 21 forming 40 a flaring top mouth and having upper supporting portions 22.

What is claimed is:

1. An ash pan of the class described including side and end walls and bottom sections having interiorly arranged water spaces, the side and end walls being composed of inner and outer sheets, the inner sheet being spaced from the outer sheet at the top to provide overflow outlets, and a 45 laterally projecting hopper mounted exteriorly of the ash pan at one end thereof and having an inlet opening, the outer sheet of the end wall of the pan being provided

with an inlet opening forming an outlet for the hopper. 55

2. An ash pan of the class described including side and end walls and bottom sections having interiorly arranged water spaces, the side and end walls being composed of inner and outer sheets, the inner sheet being spaced from the outer sheet at the top to provide overflow outlets, and a guard apron or shield mounted on the outer sheet and extending inwardly over the upper edge of the inner sheet and then downwardly in spaced relation with the same to permit water to flow over the inner sheet and down the same interiorly of the ash pan. 60

3. An ash pan of the class described including side and end walls and bottom sections having interiorly arranged water spaces, the side and end walls being composed of inner and outer sheets, the inner sheet being spaced from the outer sheet at the top to provide overflow outlets, and an 65 apron or shield mounted on the upper portion of the outer sheet interiorly of the pan and composed of an upper attaching flange, a horizontal approximately connecting flange or portion, and an inner depending 70 flange, the outer horizontal flange or portion and the inner flange being arranged in spaced relation with the upper edge of the inner sheet. 75

4. An ash pan of the class described including side and end walls and oppositely inclined bottom sections, said bottom sections and side and end walls being provided with water spaces having outlets to permit the water to flow interiorly of the pan, said 80 pan being provided at the bottom sections with outlets and controlling slides arranged to be cooled by water flowing from the said water spaces. 85

5. In an ash pan of the class described 90 having interiorly arranged water spaces provided with open upper ends, a shield arranged to extend over the open ends of the water spaces, whereby cinders or the like will be prevented from entering said spaces. 100

In testimony whereof I affix my signature in presence of two witnesses.

JASPER N. RALSTON.
